(57) **CLAIM**

The ornamental design for root director, as shown and described.

DESCRIPTION

FIG. 1 illustrates a perspective view of a root director.

FIG. 2 illustrates a top view thereof.

FIG. 3 illustrates a side view thereof.

FIG. 4 illustrates another side view thereof; and,
FIG. 5 illustrates a bottom view thereof.

The root director has a generally frustoconical shape, and includes a plurality of V-shaped recesses spaced around its wall.
